UNITED STATES PATENT OFFICE.

BERNHARD BOMBORN, OF BERLIN, GERMANY.

ELECTRIC HOISTING DEVICE.

Application filed April 17, 1922. Serial No. 554,103.

To all whom it may concern:

Be it known that I, BERNHARD BOMBORN, a citizen of Germany, residing at Berlin, Germany, have invented certain new and 5 useful Improvements in Electric Hoisting Devices, of which the following is a specification.

This invention relates to an electric hoisting device for use as a hoisting tackle or a 10 winch, with a rope drum, into which is placed wholly or partially the motor and the gearing. The invention is characterized by simple gearing with high gear ratio, which need only consist of toothed gearing; by the 15 possibility of allowing the rapidly rotating toothed wheels to run continually in an oil bath; by the convenient dismantling for effecting repairs; by the favourable disposition of the limiting switch for limiting the 20 hoisting movements of the load and by the convenient application of the controller.

In the drawings affixed to this specification and forming part thereof, several devices embodying my invention are illustrated 25 diagrammatically by way of example. In the drawings—

Figs. 1 and 2 show one embodiment of the hoisting device, Fig. 1 being a section on the line I—I of Fig. 2 viewed from the right, 30 Fig. 2 being a longitudinal section. The controlling rope lever 66 shown in dot and dash lines in Fig. 1, is disposed to the right of the section in Fig. 2.

Figs. 3 and 4 show a second modification, 35 Fig. 3 being a section on the line III—III of Fig. 4 viewed from the right and Fig. 4 a longitudinal section.

Figs. 5 and 6 show the hoisting device in the form of a wall winch. Fig. 5 being a 40 section on the line V—V of Fig. 6 viewed from the right and

Fig. 6 a longitudinal section. In Fig. 6 the controller ropes shown at the right of Fig. 2 are omitted.

Fig. 7 is a section of the brake device on the line VII—VII of Fig. 8 viewed from the right, and

Fig. 8 is a section of the controller on the line VIII—VIII of Fig. 7 through the traveling nut in detail.

In Fig. 2, 1 is the hoisting drum for the hoisting rope 14 which is arranged as a double rope, and is guided over a pulley on the left side in Figs. 1 and 3. The hoisting 55 drum is mounted by means of its partition 2 on the hub 3, of the electric motor casing 5,

which surrounds the motor shaft 4. The motor casing 5 is provided with a flange 6. Adjacent the other end of the drum is provided a flanged cover 7. Both flanges which 60 may be rectangular are rigidly connected by a rod 8 to which may be secured the eye 35 and by stay rods 9, 10, 11. The middle portion of the supporting rod 8 consists of two plates placed on edge. The lower rod 11 65 may at 12 be provided with a wood framing with U-irons 13 for protecting the drum from the loose rope pulley to which the load hook is attached.

In the interior of the drum is provided a 70 second partition 15. This surrounds the boss 16 of the flanged cover 7, through which passes the shaft 18, connected to the motor shaft 4 by a coupling 17, the end of the shaft 18 bearing the brake disc 19. The boss is 75 supported in partition 15. The motor pinion 20 meshes with two toothed wheels 21, 22 the spindles of which are mounted in the partitions 2, 15. On these shafts are mounted pinions 23, 24, which gear with an internally 80 toothed ring 25 rotatably mounted on the boss 16. A pinion 26 connected to the ring 25 gears with two toothed wheels 27, 28 which are mounted on stub shafts 29, 30 provided on the flange 7, and these toothed 85 wheels in turn gear with the internally toothed rim 31 of the hoisting drum 1. The rapidly rotating wheels 20, 21, 22 are completely enclosed and may continually run in oil. The wheels 21, 22 may be introduced 90 and mounted in position through two lateral openings (not shown and closed tightly by flanged covers) in the partition 2.

The operation is as follows. When the motor armature is rotating the pinion 20 95 drives the wheels 21 and 22 whose pinions 23, 24 turn the internally toothed ring 25.

The pinion 26, connected to the latter, drives the wheels 27, 28. These rotate the toothed rim 31 of the drum and thus also 100 this drum. The wheels 21, 22 rotate around their axes and simultaneously turn around the motor pinion 20 so that the wheels 21, 22 transmit both their rotation around their respective axes and their rotary movement 105 around the motor pinion by means of the intermediate gears 23, 24, 25, 26 and 27, 28 to the toothed rim 31 of the drum 1. In this manner a high transmission ratio is obtained.

Figs. 3 and 4 differ from Fig. 1, principally only by reason of the fact, that the drum 1 is surrounded by a thin sheet metal

casing 32, with slots 33 for the passage of the rope 14. The supporting rod 8 has its middle portion composed of two irons 34 which are riveted to the sheet metal casing.

5 The irons 36 of the lower rod 11 are also riveted to the sheet metal casing.

The rectangular flanges 6, 7 shown in Fig. 1 are in this case replaced by annular flanges 37, 38. To 37 is secured the motor casing 39, and to 38 the cover 40, provided with the stub shafts 29, 30 (as in Fig. 2) and with the sleeve surrounding shaft 18. By tightening the nuts 41, 42, 43, 44 the flange rings 38, 37 are forced tightly against 15 the sheet metal casing 32. The ring 37 therefore supports the motor and the ring 38 the part 40 carrying the gearing and the controlling parts to be described hereinafter.

Figs. 5 and 6 principally differ from Figs. 20 3 and 4 only by reason of the fact, that the rings 37 and 38 are in the form of wall brackets, 45, 46 with flanges 47, 48, which may be secured to a support or to a wall so that a stationary winch is provided.

25 The controlling mechanism and brake now to be described are illustrated on a larger scale in Figs. 7 and 8. They are enclosed in a hood 47 secured to the covers 7 (Fig. 1) or 40 (Figs. 4 and 6).

30 Fig. 7 shows the usual form of construction of the brake levers with the brake weight 48 for the brake disc 19. 49 is a spindle carrying a travelling nut 50. In Fig. 2 this spindle is driven direct by the wheel 28, 35 to which it is connected by aid of a flange at its left hand end. In Fig. 8, however, a separate wheel 51 is mounted thereon which is driven by the toothed wheel 26 (in this case the toothed wheels 27, 28 of Fig. 1 are 40 not arranged in a vertical plane but in a horizontal plane) by means of the toothed wheels 52, 53. When the travelling nut bears against the adjustable limiting nuts 54, 55 which can be locked in position at the end 45 of its movement its upper projection 56 (shown in dotted lines in Fig. 8 as it is actually disposed outside the section G—H) sliding along a slot in the sleeve 57, turns this sleeve 57. The roller 60 of the brake lever 50 61, which previously rested on one of the cam surfaces 58 or 59, is thus lowered into the position shown in Fig. 7 and the brake is applied. The sleeve 57 is also provided 55 with a toothed segment 62 which turns the controller 63 mounted vertically in the hood 47, and switches off the current.

In this manner the hoisting movement is stopped when the load hook reaches its highest and lowest positions.

60 The starting and stopping of the movement by hand is effected in the known manner by pulling the controlling ropes 64, 65. The double armed lever 66 transmits the movement to the sleeve 57. For a return to 65 the middle position there is provided the

known arrangement with a return spring 67.

The switch lever 66 might also be operated by electromagnets when it is desired to effect the control from a distance.

Fig. 4 shows that after removing the two 70 nuts 42 and 44 the transmission gear can be withdrawn to the right and removed as a whole provided that the pinion 20 is small enough to pass through opening in the hub 15.

I wish it to be understood that I do not desire to be limited to the exact details of construction shown and described, for obvious modifications will occur to a person skilled in the art.

I claim:—

1. Electric hoisting device comprising in combination, a hoisting drum, an electromotor located partly within said drum, a partition extending across said drum, a spindle mounted in said partition, a toothed wheel mounted on said spindle, a motor pinion in gear with said toothed wheel, an internally toothed rim formed in said drum and gearing between said wheel and said rim for transmitting onto said rim both the rotation of said wheel about its own axis and its revolution about the drum axis.

2. Electric hoisting device comprising in combination, a hoisting drum, an electromotor located partly within said drum, a casting surrounding said electromotor, a hub secured to said casting, said drum being mounted on said hub, a partition extending across said drum, a spindle mounted in said partition, a toothed wheel mounted on said spindle, a motor pinion in gear with said toothed wheel, an internally toothed rim formed in said drum and gearing between said wheel and said rim for transmitting onto said rim both the rotation of said wheel about its own axis and the revolution about the drum axis.

3. Electric hoisting device comprising in combination, a hoisting drum, an electromotor located partly within said drum, two partitions extending substantially in parallel across said drum and forming between them an oil-chamber, a spindle mounted in said partitions, a toothed wheel on said spindle within said chamber, and a pinion on said spindle without said chamber, a motor pinion in gear with said wheel, a boss supported in one of said partitions, an internally toothed ring rotatably mounted on said boss in gear with the pinion on said spindle, an internally toothed rim formed on said drum and a toothed wheel gearing with said rim and driven by said ring.

4. Electric hoisting device comprising in combination, a hoisting drum, an electromotor located partly within said drum, two partitions extending substantially in parallel across said drum and forming between them an oil-chamber, two spindles mounted

in said partitions, a toothed wheel on each of said spindles within said chamber, and a pinion on each of said spindles without said chamber, a motor pinion in gear with 5 said wheel, a boss supported in one of said partitions, an internally toothed ring rotatably mounted on said boss in gear with the pinions on said spindles, an internally toothed rim formed on said drum and a 10 toothed wheel gearing with said rim and driven by said ring.

5. Electric hoisting device comprising in combination, a hoisting drum, an electro-motor located partly within said drum, two 15 partitions extending substantially in parallel across said drum and forming between them an oil-chamber, a spindle mounted in said partitions, a toothed wheel on said spindle within said chamber, and a pinion 20 on said spindle without said chamber, a motor pinion in gear with said wheel, a boss supported in one of said partitions, an internally toothed ring rotatably mounted on said boss in gear with the pinion on 25 said spindle, an internally toothed rim formed on said drum, a toothed wheel gearing with said rim and driven by said ring, a controller, a limiting switch spindle operatively connected with said planetary 30 wheel, a traveling nut on said spindle and means adapted to be influenced by said nut for varying the operative condition of said controller.

6. Electric hoisting device comprising in 35 combination, a hoisting drum, an electro-motor located partly within said drum, two partitions extending substantially in parallel across said drum and forming between them an oil-chamber, a spindle mounted in

said partitions, a toothed wheel on said spindle within said chamber, and a pinion 40 on said spindle without said chamber, a motor pinion in gear with said wheel, a boss supported in one of said partitions, an internally toothed ring rotatably mounted on said boss in gear with the pinion on said 45 spindle, an internally toothed rim formed on said drum, a toothed wheel gearing with said rim and driven by said ring, a controller, a limiting switch spindle operatively connected with said planetary wheel, a 50 traveling nut on said spindle, a slotted sleeve in parallel with said spindle and adapted to be turned by said nut and a lever on said sleeve for operating said controller.

7. Electric hoisting device comprising in combination, a hoisting drum, an electro-motor located partly within said drum, two partitions extending substantially in parallel across said drum and forming between them an oil-chamber, a spindle mounted in 60 said partitions, a toothed wheel on said spindle within said chamber and a pinion on said spindle without said chamber, a motor pinion in gear with said wheel, a 65 boss supported in one of said partitions, an internally toothed ring rotatably mounted on said boss in gear with the pinion on said spindle, an internally toothed rim formed on said drum, a toothed wheel gearing with said rim and driven by said ring, a 70 casing surrounding said drum, a centering ring at either end of said casing and bolts traversing said rings adapted to force them against said casing, one of said rings forming a support for said boss.

In testimony whereof I affix my signature.
BERNHARD BOMBORN.
